(57) **CLAIM**

The ornamental design for a coconut bathing suit, as shown and described.

DESCRIPTION

FIG. 1 is a perspective view of a coconut bathing suit;
FIG. 2 is a front elevational view thereof;
FIG. 3 is a rear elevational view thereof;
FIG. 4 is a left-side elevational view thereof;
FIG. 5 is a right-side elevational view thereof;
FIG. 6 is a top plan view thereof;
FIG. 7 is a bottom plan view thereof;
FIG. 8 is a front perspective view of a coconut bathing suit thereof; and,
FIG. 9 is a rear perspective view of a coconut bathing suit view thereof.

The broken line showing of a woman wearing a coconut bathing suit in FIG. 8 and FIG. 9 is for the purpose of illustrating environmental structure and forms no part of the claimed design.
